UNITED STATES PATENT OFFICE.

ELLSWORTH A. HAWTHORNE, OF BRIDGEPORT, CONNECTICUT.

LAMP.

1,208,553.

Specification of Letters Patent. Patented Dec. 12, 1916.

Application filed February 18, 1915. Serial No. 8,994.

To all whom it may concern:

Be it known that I, ELLSWORTH A. HAWTHORNE, a citizen of the United States, residing at Bridgeport, in the county of Fairfield and State of Connecticut, have invented an Improvement in Lamps, of which the following description, in connection with the accompanying drawings, is a specification, like characters on the drawings representing like parts.

16 This invention relates to a lighting device and among other objects provides a simple and effective contact arrangement for completing the circuit from a battery to a lamp 15 and for locating the battery in its casing.

The character of the invention may be best understood by reference to the following description of an illustrative embodiment thereof shown in the accompanying 20 drawing; wherein—

Figure 1 is a vertical section through an illustrative lighting apparatus shown herein as embodying the invention. Fig. 2 is a plan of the apparatus shown in Fig. 1 with 25 the cover removed. Fig. 3 is a plan view of the cover inverted. Fig. 4 is a sectional detail showing a contact construction, and Fig. 5 is a sectional detail farther illustrating the said contact construction.

30 Referring to the drawing, the illustrative lighting apparatus shown thereon as embodying the invention comprises a casing 1 preferably of cylindrical shape appropriate to receive a standard dry battery cell 3 35 provided with binding posts 5 and 7 having nuts 5^a and 7^a threaded thereon.

The casing has a cover 8 provided with an inwardly curved flange 8^a with notches 8^b adapted to be inserted over knoblike projections 8^c adjacent the top of the casing. A slight rotation of the cover after being thus 40 inserted will lock the same to the casing.

The casing may be provided with handles 45 9 and a bail 11 to permit the ready carrying of the same and manipulation as an exploring lantern. At one side of the casing is an aperture having a flange 13 in which is secured a lamp socket 15 adapted to receive a miniature electric lamp 17 of usual construction. Encircling said socket is a holder 19 secured to the casing 1 by tabs 21 entered 50 through slits in said casing and bent back against the inner wall of said casing. The front of this holder is made concave to receive a reflector 23 having a lip 25 for engagement with said holder to secure the

reflector thereto. The outer edge portion of the reflector is formed to present a shoulder 25 and a bead 27. A glass 29 is seated on said shoulder and is retained in position 60 by a split ring 31 adapted to be snapped into said bead.

An important feature of the invention relates to electrical connecting means between the lamp and the battery for connecting one 65 of the terminals of said battery to said lamp and positioning the battery in the casing. To accomplish this there is provided a spring finger 33 having its lower end connected to the casing by rivets 35. A strip 70 37 of fiber or other appropriate insulation is interposed between said finger and said casing. The finger is further insulated from said casing by washers 39 (Fig. 5) encircling said rivets. The contact finger extends 75 upward past the lamp socket in position to be engaged by a contact on the electric lamp bulb plug when the same is screwed into its socket. The finger projects upward and is bent to offset the same somewhat from 80 the wall of the casing. Its inherent resiliency tends to move the same away from said wall. The inner face of the finger may be provided with a pair of longitudinal ribs 41 (Figs. 2 and 4) having a groove between 85 them. The face of the finger thus constructed conforms to the periphery of the binding post nut 7^a, and forms therewith an interlocking joint wherein, in the example shown, the spring finger 33 is a channeled or grooved female portion and the post 7^a a coöperating male portion.

The battery is dropped into the casing 1 with its binding post 7 opposite the contact finger 33. In the course of the downward 95 movement of said battery the binding post nut 7^a engages said finger and depresses the same somewhat back toward the wall of the casing, causing the same to be pressed into intimate engagement with said nut thereby 100 insuring the maintenance of an efficient electrical contact between said nut and finger. The curved periphery of the nut seats in the groove between the ribs of the finger and thereby tends to prevent any turning of the 105 battery within the casing and thereby prevents any breaking of the contact between said nut and said finger from such turning. This is further prevented by the fact that the finger presses the battery into close frictional engagement with the wall of the 110 casing opposite to said finger. By the con-

struction described it will be observed that the connection between the finger and the binding post nut is obtained automatically in the course of the dropping of the battery 5 into the casing and without the necessity of any adjustment of parts.

Having described the electrical connection between the lamp and one of the binding posts, next will be described the electrical connection from the other binding post with the casing in order to complete the circuit to the lamp. This, as shown herein, is accomplished through the cover referred to. On the under face of said casing is a spring 5 clip 43 mounted on a strip 45 of fiber or other suitable insulation material, said clip and strip being secured to said cover by rivets 47 passed through insulation washers 49 on the outer face of said cover. This clip as shown herein is substantially S-shaped with reverse bends presenting a bight 51 normally seated against said strip 45. To connect the binding post 5 with said clip there is provided an insulated wire 53 having metal eyes 55 at the ends thereof. One of these eyes is inserted over the binding post 5 and is secured in place by the nut 5^a and the other eye is inserted over the free end of clip 43 past the bight 51 thereof. This eye is preferably oblique to the length of the clip so that the spring effect of the latter tends to press said eye flat against the insulation strip 45 thereby securely locking said eye to said cover. It will be observed that the eye may be very quickly inserted over the clip and snapped in place without the necessity of further manual adjustment.

As stated, the clip is insulated from the cover. Hence the circuit is not completed to the casing. To accomplish this a switch device is provided whereby the light may be turned on or off as desired. To accomplish this a switch member 57 is pivoted to the under face of the cover on a rivet 59. The tail end of the clip 51 is extended somewhat beyond the insulation strip 45 as at 61 and overlaps one end of the lever 57. The lever extends outward through a slot in the cover presenting a depending grasping portion 63 conveniently adjacent the handles. When the switch lever 57 is turned to the position shown in dotted lines in Fig. 3 it will contact with the tail end 61 of the clip and thus the circuit will be completed through the cover and casing to the lamp thereby lighting the same. When, however, the switch lever is swung to its position shown in full lines in Fig. 3, its connection with the tail end of the clip is broken and the circuit to the lamp is broken. The tail end of the clip may have sufficient resilience to press the lever against the under face of the cover and thereby hold the same against inadvertent dislocation.

Having described one illustrative embodiment of the invention without limiting the

same thereto, what I claim as new and desire to secure by Letters Patent is:

1. In combination, a battery having terminals, a battery casing carrying an electrically operated mechanism and connections between said battery terminals and the mechanism including a spring member carried by said casing and in electrical connection with said mechanism, said member adapted to bear against one of the battery terminals and to exert a resilient thrust thereon in one direction and having a flanking portion engaging said terminal and resisting movement thereof in a direction transverse to that of said thrust. 80

2. In combination, a battery having terminals one of said terminals being of rounded form, a battery casing carrying an electrically operated mechanism, and connections between said battery terminals and the mechanism including a spring member carried by said casing and in electrical connection with said mechanism said member being adapted to bear resiliently against the rounded surface of said one terminal and having laterally disposed rib portions defining between them a groove to receive said surface. 90

3. In combination, a battery having terminals, a battery casing carrying an electrically operated mechanism and connections between said battery terminals and the mechanism including a spring tongue of sheet metal carried by said casing and in electrical connection with said mechanism, 95 said tongue arranged to bear resiliently against one of the battery terminals and having embossed longitudinal ribs disposed laterally and forming between them a groove presented toward said terminal to receive the same. 100

4. The combination of a battery having a terminal with a casing therefor, a cover for said casing, a spring clip secured to said cover and an electrical connection having 110 eyes, one adapted to be secured to said terminal and the other adapted to be inserted over said clip.

5. The combination of a battery having a terminal with a casing, a cover for said casing and means to complete the battery circuit including a spring clip attached to the cover and a connection from said terminal to said clip having an eye adapted to be snapped over said clip. 115 120

6. The combination of a battery having a terminal with a casing, a cover for said casing and means to complete the battery circuit including a spring clip and a flexible connection from said terminal to said 125 clip having an eye adapted to be inserted over said clip and locked thereby.

7. The combination of a battery having a terminal with a casing, a cover for said casing and means to complete the battery 130

circuit including a spring clip attached to the cover, an insulation member interposed between said clip and said cover and a connection from said terminal to said clip having an eye for insertion over said clip and adapted to be locked thereby.

8. The combination of a battery with a casing, a cover for said casing and means to complete the battery circuit including a 10 spring clip, an electrical connection having an eye clamped by said clip to said cover

and a switch pivoted to said cover movable to and from engagement with said clip to make and break the circuit.

In testimony whereof, I have signed my name to this specification, in the presence of two subscribing witnesses.
